UNITED STATES PATENT OFFICE.

WILLIAM PETER GELABERT, OF FULTON, MISSOURI.

COMBINED STRAP AND STRAP-LOOP.

No. 878,519.

Specification of Letters Patent.

Patented Feb. 11, 1908.

Application filed March 16, 1907. Serial No. 362,726.

To all whom it may concern:

Be it known that I, WILLIAM PETER GELABERT, of Fulton, in the county of Cal-
laway and State of Missouri, have invented
5 certain new and useful Improvements in
Combined Strap and Strap-Loops; and I do
hereby declare the following to be a full,
clear, and exact description of the inven-
tion, such as will enable others skilled in the
10 arts to which it appertains to make and use
the same.

My invention relates to an improvement
in harness and more particularly to an im-
proved double loop and means for attaching
15 the same to a strap,—the object of the in-
vention being to provide simple and efficient
means for securing a double loop to reversible
straps of different thicknesses.

With this object in view the invention
20 consists in certain novel features of con-
struction and combinations and arrange-
ments of parts as hereinafter set forth and
pointed out in the claims.

In the accompanying drawings, Figure 1
25 is a view in perspective of my improvement
and Fig. 2 is a side view. Fig. 3 is a longi-
tudinal sectional view.

A represents a buckle which may be of any
desired form or construction. The tongue
30 a extends through a hole b in the strap to
which the buckle is attached, the end B' of
the strap being looped back upon the body
of the strap B.

A loop C is constructed with a cross bar c
35 which has formed integral therewith a per-
forated plate c' which projects forwardly
from said cross bar and hence forwardly from
the body of loop C. Through the plate c' is
40 inserted a rivet F which passes through the
two thicknesses B' B² of the looped end of
the strap, and serves to firmly secure them
together and form a neat and flattened
looped strap end for securing the buckle
45 against displacement. By using different
lengths of rivets, the loops may be secured
to very thin or very thick straps, and in each
and all cases produce a neat and compact
looped end for the buckle. The outer end of
50 the loop is combined with outwardly curved
arms E E, which are united by a cross bar
E' forming a loop of sufficient depth be-

tween the cross bar E' and the cross bar c,
to admit of straps of any desired thickness
and insure the desired flexibility of the
looped ends of the strap.

55

When the device is used with a thick strap,
the perforated plate c' will preferably be
placed against the under side of the strap as
shown in the drawing, but with a strap, of
moderate thickness, the plate c' may be 60
placed against the top face of the strap,
while with straps of double thickness, said
plate will preferably be inserted between the
overlying portions of the strap.

The opposite side of the loop is furnished 65
with two projecting arms d, d which are con-
nected by a cross bar F' thereby forming a
closed loop for the passage of two thicknesses
of the strap.

By means of my improvement I obtain a 70
combined loop and buckle which may be
readily applied to straps of varying thick-
ness and will insure a neat flattened strap
loop for retaining the buckle in place and
which will afford ample room for the folds 75
of a strap of varying thicknesses.

Having fully described my invention what
I claim as new and desire to secure by Let-
ters-Patent, is:—

1. A strap loop having a cross bar at each 80
end, a plate integral with one of the end bars
and projecting forwardly therefrom, said
plate having a rivet hole, and a rivet passing
through said hole for securing two members
of a looped strap at a point beyond one end 85
of the body of the loop.

2. The combination with a buckle and a
looped strap engaging a member of the
buckle, of a loop having a cross bar at each
end, the end bar of the loop nearest the 90
buckle having an integral plate projecting
forwardly therefrom toward the buckle, and
a rivet passing through said forwardly pro-
jecting loop and the two members of the
strap loop which engages the buckle. 95

In testimony whereof, I have signed this
specification in the presence of two sub-
scribing witnesses.

WILLIAM PETER GELABERT.
